US00D472229S

(12) United States Design Patent **(10) Patent No.:** **US D472,229 S**
Amiya **(45) Date of Patent:** **** Mar. 25, 2003**

(54) SOUND AMPLIFIER

D349,719 S * 8/1994 Ohta D14/188
D415,493 S * 10/1999 Shiebe D14/188
D438,192 S * 2/2000 Asa D14/188

(75) Inventor: **Eizo Amiya, Shizuoka-ken (JP)**

* cited by examiner

(73) Assignee: **Yamaha Corporation, Hamamatsu (JP)**

Primary Examiner—Nanda Bondade
(74) Attorney, Agent, or Firm: Weingarten, Schurgin,
Gagnebin & Lebovici LLP

(**) Term: **14 Years**

(57) CLAIM

(21) Appl. No.: **29/136,481**

The ornamental design for a sound amplifier, as shown.

(22) Filed: **Jan. 31, 2001**

DESCRIPTION

(30) Foreign Application Priority Data

Aug. 4, 2000 (JP) 2000-021542

FIG. 1 is a front view of a sound amplifier;

(51) LOC (7) Cl. **14-03**

FIG. 2 is a rear view thereof;

(52) U.S. Cl. **D14/188**

FIG. 3 is a top view thereof;

(58) Field of Search D14/160-165,

FIG. 4 is a left-side view thereof;

D14/167-168, 188, 193-198, 135-136;

FIG. 5 is a right-side view thereof; and,

455/344-345, 347, 350-351

FIG. 6 is a bottom view thereof.
